UNITED STATES PATENT OFFICE.

JAMES H. SMITH, OF GLOUCESTER, MASSACHUSETTS.

DESIGN FOR AN ORNAMENT FOR AUTOMOBILE RADIATORS.

Application filed December 14, 1927. Serial No. 24,485. Term of patent 7 years.

To all whom it may concern:

Be it known that I, JAMES H. SMITH, a citizen of the United States, residing at Gloucester, in the county of Essex and State of Massachusetts, have invented a new, original, and ornamental Design for Ornament for Automobile Radiators, of which the following is a specification, reference being had to the accompanying drawing, forming part thereof.

Figs. 1, 2, and 3 are plans, side and front views, respectively, of a radiator ornament, showing my new design.

I claim:—

The ornamental design for an ornament for automobile radiators, as shown.

JAMES H. SMITH.
